UNITED STATES PATENT OFFICE.

CHARLES H. SCHURR AND ERNEST J. LEES, OF CLEVELAND, OHIO, ASSIGNORS TO THE LEES-BRADNER COMPANY, OF CLEVELAND, OHIO.

SWIVEL-HEAD.

1,355,855.

Specification of Letters Patent. Patented Oct. 19, 1920.

Application filed March 18, 1918. Serial No. 223,067.

To all whom it may concern:

Be it known that we, CHARLES H. SCHURR and ERNEST J. LEES, both citizens of the United States of America, residing at 6210 5 Carnegie avenue, city of Cleveland, in the county of Cuyahoga and State of Ohio, have invented a new and useful Improvement in Swivel-Heads, of which the following is a specification, the principle of the invention 10 being herein explained and the best mode in which we have contemplated applying that principle, so as to distinguish it from other inventions.

Our invention pertains to a swivel head 15 adapted for use on thread milling machines of the type exemplified in the drawings.

Conditions in thread milling machine design are peculiar and exacting and do not allow much latitude in designing chiefly because the driving pinion must be smaller in 20 diameter than the cutter. Just as stress is the power applied and strain is the result of stress, so torque is the power applied and its concomitant is torsion having as its result- 25 ant a twist factor of error, which increases in direct proportion to the length of the shaft by which the power is transmitted. Consequently, the employment of comparatively short shafts in a swivel head enables 30 the communication of a given amount of power therethrough with a measurable decrease in the torsional action and therefore with a lessening of irregularity in the action 35 of the cutter which is the terminal of the driving connection through the swivel head. Moreover, if the speed reduction is accomplished close to the point of load the latter is more satisfactorily taken care of. Mindful of this we have striven to bunch a 40 greater number of the gear elements of the power transmission whereby shorter lengths of the shafts result, and have located such compactly assembled cutter drive gearing as closely as possible to the cutter so as to enable 45 an increase in the power transmitted to the latter without disturbing its uniformity and hence reliability of action.

Accordingly, one object is to accomplish a reduction in torsion by the elimination of 50 long shafts, and therefore an avoidance of a jerky action on the part of the cutter. A further object has been to design an automatic machine accessory of the character stated which will be compact and have a 55 rigid uncomplicated drive. Another object

was to enable fine angular or turning adjustments and yet have the parts hold a chosen position relative to each other while such are being thus secured. An incidental improvement consists in enabling the 60 pivotal shaft to telescope into the swivel or single trunnion head, instead of projecting out at the rear of the machine whenever a larger work piece necessitated moving the swivel head backward.

Advertising to the drawings:

Fig. I is a front elevation of a thread milling machine embodying our invention.

Fig. II is a top view of a middle portion thereof partly in plan and partly in section 70 to disclose the entire power transmission to the cutter through the swivel head.

Fig. III is a vertical section on line III—III of Fig. II.

Fig. IV is an enlarged front elevation of 75 a portion of the machine and surmounted swivel head showing the cutter head in section.

Fig. V is a section on line V—V of Fig. III to show the train of gears from the 80 main drive shaft to the pivotal shaft in the center of the swivel head proper.

Fig. VI is a vertical and longitudinal section on line VI—VI of Fig. II.

Fig. VII is a vertical and longitudinal section on line VII—VII of Fig. II.

Fig. VIII is a vertical and longitudinal section on line VIII—VIII of Fig. II.

Fig. IX is a vertical cross-section on line 90 IX—IX of Fig. II to show the train of gears from a countershaft to the counter-spindle.

The machine comprises a bed 1 carrying at opposite ends a tail stock 2 and a head stock in which a work spindle 3 is rotatably 95 mounted and which spindle is in harmonious connection by means of mechanism including an indexing train 4 with a lead screw 5 which is in turn operatively connected with a saddle 6 movable upon a longitudinal guideway 7 formed upon the top of the bed 1. The saddle 6 has its upper surface similarly provided with a transverse guideway 8 along which a cross feed slide 9 is adapted to be moved. The crosswise 100 movement of the slide 9 is effected in the usual way by a hand wheel 10. It is this slide 9 which supports the swivel head in its entirety.

Inasmuch as this application is directed 110

solely to the construction of the swivel head and all claims are to be restricted to it, the cursory reference to the remainder of the machine is deemed sufficient and likewise 5 this mere mention that the primary driving shaft 11 is suitably connected in a manner not shown with the source of power at the head stock. This shaft 11 is seen in Figs. I, IV and V and is in fact splined to permit 10 of the longitudinal movement therealong of the casting 12 which is carried upon the saddle 6. The rotation of the shaft 11 is first communicated, as appears in Fig. V, to a pinion 13, thence to an idler 14 on a 15 shaft 15, thence to a gear 16 on the superimposed shaft 17, the farther end of which has keyed upon it a beveled pinion 18. The latter meshes with a beveled pinion 19 on the rear end of a transversely extending 20 spline shaft 20 as may be seen in either Figs. II or III. The spline shaft 20 is in fact what we will hereinafter refer to as the pivotal shaft by reason of its central location in the swivel head proper 21, as shown 25 in Fig. III. The head 21 is movable from front to rear relative to a suitable hollow extension 22, Fig. V, of the casting 12, in which the rear end of the shaft 22 is mounted as appears in Fig. II. The character of 30 certain jobs involving large sized blanks necessitates a rearward displacement of the swivel head proper in order to afford sufficient clearance for the engaging action of the cutter and blank. Heretofore, so far as 35 we are aware, such rearward movement on the part of the swivel head carried the pivotal shaft along with it so that it of necessity projected out through the casting 12 at the rear. Such projecting end not 40 only did not improve the appearance of the machine in respect to compactness but frequently interfered with the passage of people or increased the depth of the space required to accommodate the machine as a 45 whole. Instead of having the pivotal shaft move rearwardly with the swivel head we have arranged to have it capable of relative movement therein by having its splined construction telescope into a suitable bore 50 23 formed axially in the swivel head.

The forward end of the swivel head 21 is fashioned with a suitable recess 24 to further afford the necessary room for movement of the cutter. The rear end of the swivel head 55 21 carries a worm gear 25 shown in Figs. II and VI which is capable of being rotated by means of a worm 26 engaging it from below and adapted to be operated by the application of a wrench to its projecting end 27. In this manner the swivel head may 60 be very easily turned to the position desired and thereafter firmly secured by means of the fixing screws 27^a shown in Figs. II and VIII. Mounted upon the pivotal shaft 20 is a pinion 28 which meshes with a gear

29 to be seen in Figs. II and VII. The gear 29 is keyed to a short shaft 30 which is axially disposed in a housing 31 provided with a cover 32 as shown in Fig. VII. The forward end of the shaft 30 carries a bevel pinion 33 in mesh with the bevel gear 34 as may be seen in Figs. II and VIII. The gear 34 is keyed to another short shaft 35, which latter also carries a pinion 36 which is in mesh with an idler 37 so as to communicate power through it to another pinion 38 on the cutter spindle 39 as may be seen upon inspection of Figs. II, IV and IX. The cutter spindle 39 has a projecting extremity 40 provided with a securing nut 41 by means of which the cutter 42 may be held in place in the manner shown in Figs. I, II and IV.

It may be observed that the design of our swivel head permits of a very compact construction but more vitally accomplishes a collection of the speed reduction gearing between the pivotal shaft 20 and the cutter in such a manner as to involve a series of very short shafts and thereby reduce the objectionable occurrence of error attending an excessive torsion or twist action due to the applied torque. We thereby minimize the likelihood of occasioning unsteady and ununiform action on the part of the cutter and therefore lack of precision in the work to be performed by it. Moreover, by having the reduction gearing of the power transmission from the shaft 11 to the cutter 42 as closely as possible to the latter its own power is increased and its performance correspondingly improved.

We claim:

1. A swivel head comprising the combination of a bed, a saddle and a slide carried by and movable relatively to said bed and relatively to each other, a head swiveled upon said slide and fashioned about its axis with a bore, a gear coaxially carried by said head, and a pivotal shaft splined to said gear and adapted for axial movement through it and into said bore.

2. A swivel head comprising the combination of a support, a saddle longitudinally movable therein, a slide movable in a cross-wise direction upon said saddle, a hollow head swiveled upon said slide, a member carried by said head and having a bore in communication with the hollow in said head, and a shaft in telescopic connection with said member and adapted to have one end move therethrough and into the hollow of said head.

3. A swivel head comprising the combination with a driving shaft and slide movable relatively thereto, of a housing structure including a head pivotally mounted upon said slide, a pivotal shaft mounted axially of said head and constantly connected with said driving shaft, a pinion on said

- pivotal shaft, a cutter spindle and a pair of short shafts all mounted in said housing structure, one of said short shafts being parallel to said pivotal shaft, a gear on said 5 last mentioned stub shaft in mesh with said pivotal shaft pinion, a bevel pinion and bevel gear on said short shafts respectively and in mesh with each other, and gearing connecting said spindle with the other of said 10 short shafts.
4. A swivel head comprising the combination of a splined driving shaft, a support movable therealong, a head swiveled upon said support, a pivotal shaft in said 15 head and operatively connected with said driving shaft, said shafts being relatively transverse, a housing structure carried by said head, a cutter spindle mounted in said structure parallel with said driving shaft, a 20 pair of comparatively short shafts mounted in said housing at right angles to each other and speed reduction gearing upon said last mentioned shafts and upon said pivotal shaft and spindle for operatively connecting 25 the two latter.
5. A swivel head comprising the combination with a support in which is pivoted a head, a driving shaft, a housing structure carried by said head, a pivotal shaft arranged 30 axially of said head and operatively connected with said driving shaft, a cutter spindle mounted in said housing structure perpendicularly to said pivotal shaft and a transmission train connecting said spindle 35 with said pivotal shaft and including two short shafts at right angles to each other and reduction gearing adapted to transfer rotary motion from one to the other with a lessened torsion, steadier action and increased power.
6. A swivel head comprising the combination with a driving shaft and a movable support in which is pivoted a head, said support and shaft being capable of distinct 45 relative movement in transverse directions, a housing structure carried by said head, a pivotal shaft arranged axially of said head and operatively connected with said driving shaft, a cutter spindle mounted in said 50 housing structure and adapted to assume a position parallel with said driving shaft, a pair of gears upon said pivotal shaft and spindle respectively, two angularly related
- shafts also mounted in said housing structure, and mechanism including gears upon 55 said last mentioned pair of shafts for operatively connecting said cutter spindle with said pivotal shaft.
7. A swivel head comprising the combination of a driving shaft, a support movable in right angularly related directions relatively thereto, a housing structure including a head swiveled at one point upon said support, a pivotal shaft mounted for both rotary and axial movement in said 60 head, said pivotal shaft being operatively connected with said driving shaft, said head being fashioned with a bore beyond the inner end of said pivotal shaft, a cutter spindle carried by said head, and gearing 65 operatively connecting said pivotal shaft and spindle, the arrangement being such that said support may be moved along the axes of said driving and pivotal shafts respectively.
8. A swivel head comprising the combination of a splined driving shaft, a support 70 slidably connected therewith, a head swiveled upon said support, another splined shaft slidably connected with said head axially thereof and operatively connected with and in perpendicular relation to said driving shaft, a housing structure carried by said head, a cutter shaft mounted in said 75 structure, and mechanism including a plurality of stub shafts and speed reduction gearing in said housing for operatively connecting said head-axial and cutter shafts.
9. A swivel head comprising the combination of a splined driving shaft, a support 80 movable therealong, a head swiveled upon said support, a pivotal shaft in said head and operatively connected with said driving shaft, said shafts being relatively transverse, a housing structure carried by said 85 head, a cutter shaft mounted in said structure, and speed reduction gearing in said housing and arranged to make two right angular power transferences for operatively connecting said pivotal and cutter 90 shafts, said last mentioned shafts being likewise relatively transverse.

Signed by us, this 28th day of February, 1918.
